UNITED STATES PATENT OFFICE

VESPER ANDERSON SCHLENKER, OF ORANGE, NEW JERSEY

SOUND REPRODUCER

Application filed February 6, 1928. Serial No. 252,194.

This invention relates to the art of sound reproduction, and more particularly to a method and apparatus for converting electrical currents into sound waves, and has 5 particular application to the reproduction of sound from electrical currents derived from received radio or similar signals, or from mechanical records thereof, as in electrical phonographs.

10 It has been customary in the past, for the purpose of reproducing sounds from electrical currents, such as those flowing in the output of an audio amplifier, to transform such currents into mechanical vibrations of a relatively small diaphragm and to amplify such vibrations acoustically by means of horns, trumpets, and similar devices. While a high quality of sound reproduction is possible with such devices, nevertheless, the apparatus required is relatively bulky and expensive to 15 house in a pleasing and artistic manner, and expensive to ship. In particular, if it is desired to reproduce faithfully the relatively lower frequencies, as the lower pitch notes of 20 the pipe organ, the horn required in such apparatus is of such excessive size as practically to prevent its utilization by the average person in the home.

It has also been proposed to utilize diaphragms radiating to the open air, such for 25 example as cones and the like, and generally speaking, the quality of reproduction obtainable from such devices may be made to equal or exceed the quality obtainable from horns occupying substantially the same space. 30 However, even with the best types of such direct radiating devices, the quality of reproduction obtainable is far from satisfactory as can be observed by a direct comparison between the original sound to be reproduced and 35 the reproduction thereof obtainable from such a device.

It is an object of this invention to provide 40 a method and apparatus which will be capable of reproducing sounds with a fidelity closely approaching the original sounds to be reproduced, and with a volume substantially corresponding thereto.

It is a further object of my invention to 45 provide a direct radiating diaphragm which

will occupy a relatively small space, but which will, at the same time, be capable of delivering sound with a volume and quality closely approaching the original sound over the entire audible spectrum, and more particularly 55 at the high and low ends of the spectrum.

It is a further object of my invention to provide a vibratile diaphragm so arranged that although of finite size, it operates mechanically and acoustically as though it were of infinite size.

It is a further object of my invention to provide a vibratile diaphragm so arranged that its reaction back upon the driving motor is substantially zero within the range of frequencies to be reproduced.

Still other objects and advantages of my invention will be apparent from the specification.

The features of novelty which I believe to be characteristic of my invention are set forth with particularity in the appended claims. My invention itself, however, both as to its fundamental principles and as to its particular applications will best be understood by reference to the specification and accompanying drawing, in which:

Figure 1 is an elevation of the rear side of a sound reproducer according to my invention.

Figure 2 is a section on lines 2-2 of Figure 1.

Figures 3 and 4 are detail sectional views of alternate arrangements for clamping the diaphragm in the frame.

Figure 5 is a sectional view of the driving coil.

Figure 6 is an elevation of the rear side of one form of frame with the damping unit holders removed.

Figures 7 and 8 are sections thereof on lines 7-7 and 8-8 respectively.

Figure 9 is a diagram showing the operation of my diaphragm.

Figures 10 and 11 are respectively sectional and front elevation views of the driving motor, Figure 10 being a section on lines 10-10 of Figure 11.

Figure 12 is a detail sectional view of the driving motor showing one method of bring-

ing the leads out from the driving coil; Figure 12^a is an elevation of the conductor carrier employed in Figure 12.

Figure 13 is a front elevation of a free edge diaphragm mounted in a housing according to my invention and,

Figure 14 is a section taken on lines 14—14 of Figure 13.

In accordance with my invention I provide a diaphragm of vibratile material radiating directly to the open air without the interposition of a horn or similar device, and a driving motor for vibrating said diaphragm, the diaphragm and driving motor being so arranged that reflected waves do not react back upon the driving motor. As compared with the diaphragms usually used in horn type reproducers, the diaphragm is of relatively large size. The size, however, is of minor importance, but it should be understood that generally speaking, the smaller the diaphragm the less will be the radiation of the diaphragm at low frequencies: that is to say, the low frequency cut off point rises as the diaphragm is made smaller.

I have found that satisfactory results may be obtained by the use of a clamped edge diaphragm approximately 24" on each side and in the general form of a square, modified as hereafter described; in fact, I have found that a diaphragm of such size when arranged and operated in the manner which will hereafter be described in detail, will give a quantity and quality of sound reproduction far superior to anything now obtainable on the market, radiating at full efficiency from about 85 cycles to over 5,000 cycles, with a substantially flat response characteristic over the entire included band of frequencies.

In accordance with one form of my invention, I provide a flat diaphragm of extremely thin and light material, capable of sustaining considerable tension. I have found that a very satisfactory material for such a diaphragm is metal, although other materials, such as plywood, may be used, according to another embodiment of my invention. Particularly satisfactory results are obtained from aluminum alloys rolled in the form of a sheet, having a thickness of approximately .002 of an inch. As such materials may be obtained on the market and constitute per se no part of my invention, it is not believed necessary to describe them in detail.

The vibratile material of the diaphragm is mounted upon a supporting frame consisting of a pair of clamping members extending around the periphery of the diaphragm, and the diaphragm is arranged to be held in position with a tension in the material of about forty pounds per inch in the case of aluminum alloys referred to. The tension of the diaphragm, it should be understood, must be at all times maintained within the elastic limit of the material used, as

otherwise the material will be stretched and permanently deformed, which will seriously affect the reproduction. The tension should be made as great as possible for the purpose of raising the speed of travel of flexural vibrations in the material, since the efficiency of a direct radiator depends upon the degree of coupling between the air and the diaphragm, which in turn is a function of the ratio of the velocity of propagation of waves in the diaphragm to that of waves in the air. Mathematically, the optimum radiation would be obtained in case this ratio were made equal to unity, by stretching the diaphragm sufficiently. However, it is evident that the elastic limit of the material of the diaphragm limits the amount of tension which can safely be used.

In accordance with another form of my invention, I may use an acoustically free edge diaphragm made up of material which is so chosen as to have considerable stiffness together with minimum mass. Satisfactory results have been obtained by the use of a plywood diaphragm made up of thin layers of balsa wood, glued together, with the grain crossed. Such a diaphragm has considerable stiffness and small mass, and I have found that satisfactory results may be obtained without applying tension to such a diaphragm, the inherent stiffness and light weight of the material contributing to afford a velocity of wave propagation in the material approaching that obtainable in the tensioned diaphragms already described.

Such a diaphragm may be operated as an acoustically free edge diaphragm affording certain advantages: for example, while the amplitude of motion at the periphery of a clamped diaphragm is zero, the amplitude of motion at the periphery of an acoustically free edge diaphragm is double the amplitude obtained at a point within the diaphragm, and this larger amplitude of vibration obtainable at the edge of such a diaphragm makes it possible to utilize a diaphragm of somewhat smaller size, without sacrificing efficiency of radiation at the lower frequencies, provided precautions are taken to prevent the surging of air around the edge of the diaphragm. This may be done by suspending the diaphragm at its periphery from a hinge of thin linen, silk or similar material having a sufficiently closely woven texture to hinder the surging of air through it, and attaching the outer edge of this hinge to a suitable baffle board or to the interior wall of a cabinet.

It has already been stated that very satisfactory results are obtainable from a tensioned diaphragm clamped at the edge, having the general form of a square 24" on a side: comparable results may be obtained by the use of a free edge diaphragm, such as

just described, in the same form, but only 12" on a side.

If vibrations be impressed upon such a diaphragm at a point within the periphery, as is well known, travelling waves are set up in the material of the diaphragm, which travel outward toward the periphery: upon reaching the periphery, such waves are reflected inwardly 180° out of phase in the case of a clamped edge, and in phase in the case of a free edge, where they interact with other waves travelling in other directions in the diaphragm. This interaction, for various reasons, I believe to be a prominent cause of distortion in the sounds reproduced by such a diaphragm, since it may cause non-uniform radiation of sound at various frequencies, accentuating certain frequencies and diminishing others, and reacting back on the drive in a complex manner.

In accordance with the preferred embodiment of my invention, I shape the periphery of the diaphragm and propagate waves therein in such a manner that after reflection at the periphery, the reflected waves present a substantially straight line wave front, and I then absorb a large part of the energy of such reflected waves after they have travelled inwardly from the periphery of the diaphragm a sufficient distance to reach a point at which they would interfere or react with other waves reflected from other parts of the periphery of the diaphragm. In general I obtain this result by arranging the periphery or boundary of the diaphragm in the shape of a parabola, and by impressing the vibrations upon the diaphragm at or near the local point of the parabola in such a manner that the vibration waves travel in a direction radially outward from the focus. As a result, after reflection, the wave front of the reflected wave will be a straight line, perpendicular to the axis of the parabola and travelling in the direction of the axis, away from the focus, in a manner analogous to the reflection of light from a source at the focus of a parabolic reflector.

I preferably arrange damping material upon the diaphragm in a line parallel to the wave front of reflected waves, whereby each reflected wave is simultaneously damped out and substantially absorbed by the damping material over its entire front. Preferably, the diaphragm is arranged to have the general shape of a square, the four sides of which, however, instead of being straight lines, are parabolic and curve inwardly to a point of intersection half way between the opposite corners. The damping material is preferably, but not necessarily, arranged in a line coinciding with the diagonals of the square and extends inwardly sufficiently far to cover the wave front of the waves reflected from the periphery. This arrangement provides what I term a "one-way" transfer of energy

from the drive to the diaphragm; that is to say, since reflected waves never return to the focus at which the driving vibrations are applied, the diaphragm does not react back on the driving motor to interfere with the propagation of new waves, which is a serious defect of all prior direct radiating diaphragms.

The damping material may be regarded as a mechanical resistance analogous to the resistance in an electrical circuit, and it is apparent that, if complete absorption is to be obtained, the mechanical resistance of the damping material should be equal to the surge impedance of the diaphragm, measured at the particular point at which the damping material is applied. When this condition is obtained, or closely approximated, mechanically the diaphragm operates with respect to the drive as though it were infinite in size; that is to say, the reflected waves are terminated at the damping material and are not reflected backward from the end point, as they would be from the boundary of a finite diaphragm. If such a diaphragm may be conceived as operating in a complete vacuum, the diaphragm may then be regarded as a mechanical power transmission line, in which power is delivered from the driving unit through the diaphragm to the damping material, where it is dissipated as heat. When the diaphragm is submerged in an energy absorbing medium, such as air, it will be understood that not all of the energy delivered to the diaphragm by the driving mechanism, is delivered to the damping material: in fact, if this condition obtained, the efficiency of the diaphragm would be zero; because of the air loading upon the diaphragm, compression or rarefaction waves are set up in the air adjacent the diaphragm, absorbing from the diaphragm a certain proportion of the energy. It will be understood that it may be permissible to depart from the mathematically exact condition in which the vibrations are completely terminated by the damping material, since a certain proportion of the energy may be allowed to pass along the diaphragm across the damping material without seriously affecting the results.

I have found that such a sound reproducer will reproduce with great faithfulness sound waves corresponding to the mechanical vibrations impressed thereon, and in order to utilize the acoustic properties of such a diaphragm to the highest efficiency, it is desirable to eliminate any possible distortion in the driving mechanism. For this reason, I prefer to use the so-called "dynamic" or "floating coil drive" in which a relatively small and light cylindrical coil is vibrated axially in an annular air gap traversed by a constant uni-directional magnetic flux. By supplying the electrical currents which it is desired to convert into sound to the vibrat-

ing coil of such a device, the coil is caused to vibrate axially with an amplitude and frequency very closely approaching the amplitude and frequency of the driving currents, and the distortion inherent in all known types of magnetic armature driving motors spring biased to neutral position, and thereby having inherent elasticity is eliminated.

The apparatus thus far described is capable of such faithfulness of reproduction, that distortion in the radio receiver or the amplifier operating it, will, in general, be greater than the distortion in the sound reproducer itself, and overloading of the tubes supplying the reproducer becomes immediately evident substantially as soon as it occurs. For this reason, in order to obtain the highest quality of sound reproduction of which my invention is capable, it is of considerable importance that the radio receiver and the audio amplifier utilized for supplying it, should be of high quality and should not be operated beyond the limits of distortionless operation, as otherwise rattling and accentuation of high frequencies appear, which, in the past, have not been particularly harmful or noticeable, since they have been masked by greater distortion in the reproducer itself.

Referring now more particularly to Figure 1, 1 designates generically a frame or peripheral clamping ring provided with a plurality of closely spaced holes 32 for the passage of clamping bolts. It will be understood that two such clamping rings 1^a and 1^b are utilized to engage and hold the diaphragm 30 tightly between them. For the purpose of supporting the driving motor and the damping units, one of the clamping frame members may be provided with cross braces 2, 3, 4 and 5, and also with inwardly extending braces 6, 7, 8 and 9, which extend inwardly to motor supporting ring 10. For the purpose of securing the damping units in position, I may provide a pair of parallel braces 16 and 17 extending from cross brace 5 to corner "C", which may be formed integral with the frame or as a separate frame and bolted thereto as shown. Similar braces 18 and 19 extend from cross brace 2 to corner "D", braces 20 and 21 from cross brace 3 to corner "A", and braces 22 and 23 from cross brace 4 to corner "B". Inwardly extending projections may be mounted upon the cross braces 2, 3, 4 and 5, to which the damping unit frames may be fastened to hold the damping material in position, and a handle 11 may be provided. Naturally, sufficient clearance must be allowed between the inner faces of these braces to permit vibration of the diaphragm, without the possibility of the diaphragm striking the braces. This will preferably be $\frac{1}{8}$ ".

It will be understood that the internal bracing portions are preferably provided only on one of the clamping frames, since these

braces are primarily for the purpose of holding the motor and damping units in position, and not necessarily for insuring structural rigidity of the rim 1.

Each frame member or clamping ring is preferably made in one piece, and preferably from the same material as the diaphragm in order to insure against changes in the tension of the diaphragm as a result of temperature variations. The holes in the ring for the clamping bolts, are preferably sufficiently close together so that a uniform tension is exerted around the entire periphery of the diaphragm, and the number and spacing of the bolts may be determined by experiment. It will be understood that in general the heavier and more massive the frame, the fewer the number of bolts necessary. Preferably, the holes in one of the frames will be tapped to receive bolts, but it will be understood that as an alternative, clamping nuts may be utilized if it is not desired to tap the frames, or, integral lugs 60 or rivets 60^a may be conveniently provided in one of the frame rings, such as 1^a, if the ring is cast, which may engage corresponding holes in the other frame ring 1^b, and may be upset or hammered to form a head, maintaining the frames 1^a and 1^b in position and thereby securing the diaphragm 30, which is heated or mechanically stretched to insure the predetermined tension.

Damping material 42, such as lamb's-wool, felt, and the like, is preferably provided in the space between braces 20 and 21, 22 and 23, 16 and 17, and 18 and 19. Various damping materials may be utilized but preferably I utilize a layer of lamb's-wool next to the diaphragm 30, which is backed by a layer of felt.

The diaphragm is driven preferably by means of an annular coil 34, which is traversed by the electrical currents which it is desired to convert into sound. The annular coil 34 moves axially in an annular air gap in magnet 37, which comprises a center pole piece 38 and a separate outer pole piece 40 carried by a spacing ring 41.

The driving coil may be mounted upon a ring 35 of conducting material, such as aluminum or copper, provided with a flange 36 at one end, by means of which the coil may be cemented to the diaphragm 30. The ring will preferably be split axially at one point to prevent its acting as a short circuited turn, but in case a filtering action is desired to suppress high frequency harmonics generated by tube overload, it may be in the form of a closed ring. The eddy current losses will then operate to dissipate a certain proportion of the energy of the higher frequencies, and the result is a suppression of high frequencies, so that distortion due to tube overload is decreased, and the use of a low-pass filter is rendered unnecessary. The coil will be made

as rigid and light as possible, and preferably consists of a small number of turns with an optimum space factor, so that the resistance is kept extremely low. In general, it may be stated that the coil assembly will be made as light as possible consistent with sufficient structural rigidity to maintain its shape in operation, thereby permitting the use of a relatively small air gap in which there may be obtained a high density of magnetic flux. The particular arrangement of the driving coil and magnet is shown in Figures 10 and 11, in which 37 designates generically a core and inner pole piece formed in what may be termed a cup with an internal projection, the internal projection 38 forming the inner pole face, and the outer portion or rim of the cup 39 resting on and making close magnetic contact with the outer pole piece 40 carried on spacing member 41 of brass or other suitable material. The outer pole piece 40 is in the form of a ring, provided with cut out portions 45 and spaced 90° from each other to permit the spacing ring 41 to rest upon internally projecting lugs 12, 13, 14 and 15 in motor supporting ring 10. The outer pole piece 40 is secured to the spacing ring 41 by means of rivets 60, 61, 62 and 63, and the spacing ring is provided with outwardly extending ears 65, 66, 67 and 68, which rest upon and engage lugs 12, 13, 14 and 15, which lugs are preferably tapped to engage screws 46, securing the spacing ring and outer pole piece rigidly within the frame ring 10. The outer face of ears 65, 66, 67 and 68 preferably are arranged to make a snug fit with the inside of motor supporting ring 10, while ample clearance is provided between the outer periphery of outer pole piece 40 and the inside of motor supporting ring 10. The outer rim portion 39 of the magnet is cut away, as at 45*, to permit access to the screws 46. It will be observed that this construction provides a cavity 43 within the center pole piece, which may be utilized for the purpose of housing an energizing winding in case the magnetic flux across the air gap is to be derived from an electromagnet, but it will be understood that the entire pole piece 37 and outer pole piece 40 may both be permanent magnets. The driving coil 34 is cemented or otherwise secured to the diaphragm 30 for axial movement in the annular gap between the inner pole piece 38 and the outer pole piece 40. The outer pole piece 40 is preferably provided with a tapered edge 48, serving to concentrate the magnetic flux lines in a small area, and the cross sectional area of the magnetic path at any point will preferably be made about four times the cross sectional area of the flux path in the air gap. The magnet is preferably held in place by means of metal straps 26 and 27.

Referring now more particularly to Figures 12 and 12*, I have shown one method of supplying currents to the driving coil 34.

Considerable care must be taken in bringing the leads to the driving coil, since the leads must be prevented from being stressed over their elastic limit during operation, as such repeated stressing would produce crystallization and ultimately result in a break or breaks in the leads. Also, care must be taken to prevent the leads chattering against other parts of the structure during operation. For the purpose of making contact to the coil, I may provide a strip 71 of relatively light and wide ribbon, such as silk, and I glue or otherwise secure thereto a pair of strips or ribbons 72 and 73 preferably of phosphor bronze, approximately .001 of an inch thick and about $\frac{1}{8}$ " wide. One end of the ribbon 71, with the conductor secured thereto, is cemented or glued to the supporting ring 35 adjacent the connection to the diaphragm at the flange 36. The two ends of the coil 34 are soldered to the conductors 72 and 73 respectively. A hole 70 is provided in the outer pole face 40 and spacing ring 41, through which the ribbon 71 is passed into the cavity 43 in the magnet 37. The ribbon is then passed through one of the cut away portions 45* to a suitable terminal block 74 whence permanent leads may be taken off to the exterior of the reproducer in any suitable manner. The ribbon 71 is preferably glued to the outer pole piece at point 75, leaving just sufficient slack to permit free vibration of the diaphragm, after which the passage 70 may be packed with damping material such as wool or felt 76. The use of a relatively wide ribbon presenting a large surface and having a minimum mass, provides a relatively heavy air damping upon the lead structure and prevents the development of vibration of excessive amplitude therein, which would tend to stress the leads beyond the elastic limit and result in crystallization.

As an alternative, when a metal diaphragm is used, it is possible to ground one end of the coil 34 upon the coil support 35 or diaphragm 30, and in this arrangement it is only necessary to provide one conducting strip upon the ribbon 71, the other side of the circuit being formed by the diaphragm and frame.

Under certain conditions, one or both of the leads may be glued or cemented to the diaphragm itself and carried upon the diaphragm to a terminal block on the frame.

Referring now more particularly to Figure 6, I have shown the frame with the damping unit supports 16, 17, 18, 19, 20, 21, 22, and 23 removed: the lugs 16*, 17*, 18*, 19*, 20*, 21*, 22* and 23* are provided on cross braces 2, 3, 4 and 5, and the damping unit frames 16—17, 18—19, 20—21, and 22—23 carrying the damping material may be bolted between lugs 16* and 17* and corner "C", lugs 18* and 19* and corner "D", lugs 20* and 21* and corner "A" and lugs 22* and 23* and corner "B" respectively.

Referring now more particularly to Figures 13 and 14, I have shown an alternative form of diaphragm, of different material, and operating with an acoustically free edge: in this arrangement, the diaphragm 80 may be formed of separate layers 81 and 82 of balsa wood, glued together, with the grain crossed. The diaphragm so constructed may be provided at its edge with a hinge mounting 83, which may be in the form of a strip of light and closely woven linen or silk fabric having its inner edge glued or cemented to the diaphragm 80, and its outer edge similarly secured to an internal carrying plate 84 mounted within the walls 85 and 86, 87 and 88, of a cabinet. The supporting hinge 83 which supports the diaphragm is preferably very light and is preferably only wide enough so that the periphery of the diaphragm is axially unrestrained and vibrates in substantially the same manner as it would if entirely free at the edge, developing twice the amplitude of vibration at the periphery as within the diaphragm. Supporting plate 84 will preferably follow the contour of the diaphragm and extend as close as possible thereto, while allowing freedom of motion of the periphery of the diaphragm, so as to obtain a minimum area of hinge consistent with freedom of motion.

As already stated, the large amplitude of vibration developed at the periphery of a free edge diaphragm permits the use of a smaller diaphragm without raising the low frequency cut off point, and such a construction may be preferred where it is desired to keep the size of the reproducer as small as possible.

It will now be understood that with the apparatus so far described, if the field magnet is energized and a fluctuating current passed through the coil 34, this coil will be caused to vibrate axially and the vibrations will thus be communicated to the diaphragm; these vibrations will travel outwardly in the material of the diaphragm in a manner similar to the outward travel of ripples upon a mill pond when the surface is disturbed as by dropping a stone in the water.

If an ordinary circular diaphragm were used instead of the arrangement herein shown, when these vibrations reached the periphery they would be reflected from the boundary backwardly toward the center of the diaphragm. This reflection would result in interaction between the reflected waves returning from the periphery of the diaphragm and the original waves travelling toward the periphery, and would result in the production of standing waves, accentuating the radiation of certain frequencies and diminishing others, and would react on the motor by causing the diaphragm and driving coil to tend to take a position other than that which it would take if the diaphragm were

in fact infinite. This will cause the mechanical impedance of the diaphragm to vary in a complex manner, seriously distorting the response characteristic: and in general, producing many undesired results, evident as various types of distortion and undesired noises.

Referring again to Figure 6, it is desired to point out that the curve formed by points D, H, E and B, is a parabola; similarly, curves A, E, F and C;—B, F, G and D;—and C, G, H and A, are parabolas. These parabolas are preferably all plotted together from the same equation and all have a focus at point K, which is the center of the driving coil. It will be observed that the diaphragm is thus made up of a central square section, bounded by the vertices E, F, G and H, and that surrounding this central section, there are four sections, A—E—H, E—B—F, F—C—G, and G—D—H. The inner boundaries of each of these outer sections, it is to be understood, are only imaginary boundaries. The other two boundaries are parabolic curves intersecting at the points A, B, C, and D. It can be shown mathematically that the angles at the points A, B, C and D, formed by the intersection of two parabolic boundaries, are right angles, but for manufacturing purposes, I prefer to round off these corners slightly, as shown, rather than to preserve the mathematical shape exactly to points A, B, C and D.

Turning now to Figure 9 in which I have shown diagrammatically the action of the diaphragm, it will be understood that vibrations impressed upon the diaphragm by the driving coil 34 cause flexural waves in the material, which travel outwardly in a direction outward from the focus K toward the periphery in the form of expanding circles, as represented by the series of concentric circles around point K.

Let us now consider the path followed by any particular point upon one of these waves as it travels outwardly. It will be seen that the path followed is a straight line: for example, a path may be assumed from K to a point P, which is any point arbitrarily selected upon the boundary E—B. Impinging upon the boundary at point P, the wave will be reflected in accordance with the laws of reflection: in other words, it will be reflected at an angle of reflection which is equal to the angle of incidence, but since E—B is a section of a parabola whose focus is at K and whose axis is on the line A—K, the path after reflection will be parallel to the axis A—K.

If a similar point Q be assumed upon the parabola B—F, the reflection of a wave from this point, will be parallel to the same axis but in the opposite direction from the path followed by the wave reflected from point P. It will be seen, therefore, that two waves

striking similar points upon the opposite boundaries E—B and F—B, are reflected toward each other in the same straight line, travelling at the same speed and will intersect on the axis K—B. The same is true of points P1 and Q1, and P2 and Q2. It will be seen that all of these paths are parallel, and since the distance K—P—O is equal to the distance K—P1—O1, which is also equal to the distance K—P2—O2, it will be observed that a circular wave travelling in a direction outwardly from the focus K, after reflection, possesses not a circular wave front but a straight line wave front, as indicated by the dotted lines parallel to the K—B axis. It is also apparent that interaction between two sets of reflected waves cannot take place until one of these has passed across the axis K—B; and if now a layer or line of damping material be laid along the axis K—B in the path of the reflected waves in a manner to absorb and dissipate the energy of such reflected waves, the reflected waves will be substantially terminated at this point, and by proper control of the damping material so that the mechanical resistance introduced at such point is equal to the mechanical surge impedance of the diaphragm measured at that point, no reflection will take place. A variation from the proper value of damping will cause reflection to take place at this point.

It will be observed that along the boundary E—F adjacent point B, the reflection is not in accordance with the laws already described, since the curve at this point departs from a true parabola, but it will be observed that when a vibration wave arrives at point B from the source K, it is necessary to pass the entire line of damping material. It results from this that the reflection action at corners A, B, C and D, for all practical purposes, may be disregarded. Since the entire diaphragm is symmetrical, an action takes place in the other quadrants similar to that already described; for example, a point on a wave travelling from K to point R or S on the boundary A—E is reflected inwardly in a direction perpendicular to the axis A—K, and the provision of damping material along the axis A—K in a manner similar to that already described, suffices to terminate this wave on the axis A—K. As a result of this arrangement, it will be seen that while the diaphragm is of finite size, it acts acoustically and mechanically as though it were of infinite size, in that waves emitted from the source K never return to the source K by reflection, and consequently do not react back upon the driving motor.

While I have referred to the damping material as being disposed upon the axis K—B, it will be understood that while this may be assumed mathematically, it is somewhat difficult to obtain in practice; and preferably,

I utilize a layer of damping material approximately an inch wide and lying on the axis K—B in the area travelled by the reflected waves. It will be understood that under certain conditions, also, it may be desirable to increase the width of this layer of damping material, so that a reflected wave begins to be damped soon after reflection. 70

While I have referred to the use of wool, felt, and similar materials, for damping, it will be understood that other arrangements may be utilized, such as air damping, which may be obtained under certain conditions simply by enclosing the air over a portion of the diaphragm, or electro-magnetic, or eddy current, damping, may be utilized by providing conductors attached to the diaphragm, moving through a magnetic field, or by the provision of magnets adjacent the diaphragm, in case it is a conductor, whereby 80 vibrations thereof cause the generation of eddy currents in the diaphragm itself. In all of these arrangements, as will be understood, the purpose and effect of the damping is to absorb the energy of vibration to a sufficient extent so that standing waves are not produced on the diaphragm and so that reflected waves are not reflected back to the driving motor, and while I prefer to apply the damping material along the four diagonals K—B, 90 K—A, K—D, and K—C, extending outwardly to the boundary of the diaphragm and inwardly to lines E—F, H—E, G—H and F—G, one or more of the damping units may be omitted, those retained being preferably in adjacent sections rather than opposite sections. Such omission, will, in general, be accompanied by distortion, due to passage of reflected waves back to the drive, but a certain amount of such reflection may be tolerated if the attenuation of the diaphragm is high or if the amplitude of vibration is kept small. 100

While mathematically there is no limit to the size of the diaphragm which may be utilized, practical considerations of cost will naturally impose a limit, beyond which it is not desirable to go. 110

It will also be understood that since the radiation of sound from a direct radiator, such as described, is governed by laws similar to those governing the radiation of electrical energy from an antenna, it will not be desirable to decrease the size of the diaphragm to a point where its size is small in 115 comparison with the longest wave length to be radiated.

I have also observed that while the low frequency cut-off point rises as the diaphragm is made smaller, if exposed to air 125 free to circulate around the periphery of the diaphragm, this cut-off point can be lowered to a certain extent by increasing the length of the minimum path necessary to be followed in travelling through the air from one 130

side of the diaphragm to the other. This may be accomplished by providing a baffle plate extending around the edge of the diaphragm or by mounting the diaphragm itself within a cabinet and securing the edge of the frame to the inner walls of the cabinet.

I have found that a sound reproducer constructed according to the principles herein disclosed, which is made approximately 24" on each side, will operate at full efficiency at a frequency as low as approximately 80 cycles, and will also operate at full efficiency at frequencies as high as 5000 to 6000 cycles, the intervening range of frequencies being covered with a substantially flat and uniform characteristic: in fact, I have found that such a reproducer is much more free from distortion than the other elements with which it is customarily operated, and whereas, with an ordinary type of cone loud speaker or horn such as is now obtainable on the market, distortions arising in the radio receiver, particularly those due to overloading of the tubes and batteries, are not evident to the lay observer, such distortions are at once evident even in as small amounts as those resulting from 5% overload when a sound reproducer according to my invention is utilized. It is therefore desirable in operating a reproducer according to my invention, to take particular pains to prevent overloading of any of the tubes feeding it, and to make sure that batteries and other current supply devices are fully capable of carrying their rated load without loss of voltage, as otherwise rattling and accentuation of high frequencies will be evident, which might erroneously be attributed to the sound reproducer itself.

While I have described the operation of my invention in the reproduction of sound from electrical energy, it will be apparent that a sound reproducer in accordance with my invention is, to a certain extent, reversible, and may be utilized as a transmitter.

Also, while I have described certain preferred embodiments of my invention, it will be understood that modifications and changes may be made without departing from the spirit and scope of my invention, as will be understood by those skilled in the art.

I claim:—

1. A sound reproducer for voice and music comprising a relatively large vibratile diaphragm adapted to be driven from a point within the periphery thereof, said periphery comprising a curve causing sound waves originating at said point to be reflected from said curve to present a straight line wave front after reflection.

2. A sound reproducer for voice and music comprising a relatively large vibratile diaphragm adapted to be driven from a point within the periphery thereof, said diaphragm comprising a plurality of sections, the periphery of each section comprising a curve

causing sound waves originating at said point to be reflected from said curve in parallel paths.

3. A sound reproducer for voice and music comprising a relatively large vibratile diaphragm having a periphery, a portion of which is substantially in the form of a portion of a parabolic curve.

4. A sound reproducer for voice and music comprising a relatively large vibratile diaphragm having a periphery, a portion of which is substantially in the form of a portion of a parabolic curve and means for propagating vibration waves therein in a direction radially outward from the focus 80 thereof.

5. A sound reproducer for voice and music comprising a relatively large vibratile diaphragm having a periphery, a portion of which is substantially in the form of a portion of a parabolic curve and means for propagating vibration waves therein in a direction radially outward from the focus 85 thereof, said driving means being substantially devoid of elasticity.

6. A sound reproducer for voice and music comprising a relatively large vibratile diaphragm, the boundary thereof having the shape of intersecting parabolic curves.

7. A sound reproducer for voice and music 95 comprising a relatively large vibratile diaphragm, the boundary thereof having the shape of intersecting parabolic curves having a common focus.

8. A sound reproducer for voice and music 100 comprising a relatively large vibratile diaphragm, having a central section and a plurality of outwardly extending sections surrounding said central section, said outwardly extending sections having parabolic boundaries.

9. A sound reproducer for voice and music comprising a relatively large vibratile diaphragm having a central section, and a plurality of outwardly extending sections surrounding said central section, the boundaries of said outwardly extending sections being 110 similar parabolic curves having a common focus.

10. A sound reproducer for voice and 115 music comprising a relatively large vibratile diaphragm having a periphery, a portion of which is substantially in the form of a portion of a parabolic curve, means for propagating vibrations therein in a direction radially outward from the focus thereof, and damping material mounted thereon in a line parallel to the wave front of reflected waves.

11. A sound reproducer for voice and 125 music comprising a relatively large vibratile diaphragm having a periphery in the form of intersecting parabolic curves, means for propagating vibration waves therein in a direction radially outward from the foci thereof, and damping material mounted thereon in 130

a line parallel to the wave front of reflected waves.

12. A sound reproducer for voice and music comprising a relatively large vibratile diaphragm having a periphery in the form of intersecting parabolic curves having a common focus and also having a line of maximum amplitude of vibration, means for propagating vibration waves therein in a direction radially outward from said focus, and damping material mounted thereon along the line of maximum amplitude of vibration.

13. A sound reproducer for voice and music comprising a relatively large vibratile diaphragm having a central section and a plurality of outwardly extending sections surrounding said central section, said outwardly extending sections having parabolic boundaries disposed about a common focus and also having a line of maximum amplitude of vibration, means for propagating vibration waves therein in a direction radially outward from said focus, and damping material associated with a plurality of said outwardly extending sections along the line of maximum amplitude of vibration.

14. A sound reproducer for voice and music comprising a relatively large vibratile diaphragm having a periphery in the form of intersecting parabolic curves having a common focus and having axes at right angles to provide a diaphragm having an axis of symmetry, means for propagating vibration waves therein in a direction radially outward from said focus, and damping material associated therewith in the path of reflected waves and along the axis of symmetry of said diaphragm.

15. A sound reproducer for voice and music comprising a relatively large vibratile diaphragm having a periphery comprising a portion of a parabola, means for propagating vibration waves in a direction radially outward from the focus of said parabola, and damping material mounted on said diaphragm in a line perpendicular to the axis of the said parabola.

16. The method of converting mechanical vibrations into sound waves corresponding thereto, which comprises impressing said vibrations on a relatively large vibratile diaphragm at a point within the periphery to produce travelling waves in the material of said diaphragm, reflecting said waves from various portions of the periphery of said diaphragm in a manner to produce after reflection a plurality of straight line wave fronts, permitting said reflected waves to travel inwardly from said periphery, and absorbing the energy of said reflected waves to prevent interaction between waves reflected from different portions of said periphery.

17. The method of converting mechanical vibrations into sound waves corresponding thereto, which comprises impressing said

motion upon a relatively large vibratile diaphragm to produce travelling waves therein, reflecting said waves from the various portions of the periphery of said diaphragm in such manner as to produce waves having a straight line front after reflection, permitting said reflected waves to travel inwardly from said periphery and absorbing the energy of said reflected waves at a plurality of points on said diaphragm simultaneously to prevent interaction between waves reflected from different sections of said periphery.

18. The method of converting mechanical motion into sound waves corresponding thereto with a relatively large vibratile diaphragm having a periphery in the form of intersecting parabolas having a common focus, which comprises applying said motion to said diaphragm in a manner to produce therein vibration waves in said diaphragm travelling in a direction radially outward from said focus, reflecting said waves from the periphery of said diaphragm, permitting said reflected waves to travel inwardly from said periphery, and absorbing the energy of said reflected waves over the entire reflected wave front simultaneously to prevent interaction between waves reflected from different portions of said periphery.

Signed at New York city, in the county of New York and State of New York, this 28th day of January, A. D. 1928.

VESPER ANDERSON SCHLENKER.
